BY Drake G. ATTY'S.

UNITED STATES PATENT OFFICE.

ALBION ALEXANDER VANDERPOOL, OF NEWARK, NEW JERSEY.

BURGLAR-ALARM CIRCUIT-CLOSER.

SPECIFICATION forming part of Letters Patent No. 542,697, dated July 16, 1895.

Application filed November 8, 1894. Serial No. 528,266. (No model.)

To all whom it may concern:

Be it known that I, ALBION ALEXANDER VANDERPOOL, a citizen of the United States, residing at Newark, in the county of Essex and State of New Jersey, have invented certain new and useful Improvements in Bur- 5 glar-Alarm Circuit-Changers for Windows; and I do hereby declare the following to be a full, clear, and exact description of the in- 10 vention, such as will enable others skilled in the art to which it appertains to make and use the same, reference being had to the accompanying drawings, and to letters of ref- 15 erence marked thereon, which form a part of this specification.

The objects of this invention are to reduce the cost of construction, obtain a more sim- 20 ple and compact device, secure a greater cer- tainty and efficiency of action, and to gain other advantages and results, some of which 25 will be referred to in connection with the de- 30 scription of the working parts.

The invention consists in the improved bur- 35 glar-alarm circuit-changer for windows and in the arrangements and combinations of parts, all substantially as will be hereinafter set forth, and finally embraced in the clauses of the claim.

Referring to the accompanying drawings, 40 in which like letters indicate corresponding parts in each of the figures, Figure 1 is an edge view, and Fig. 2 a plan, of the improved device. Fig. 3 is a perspective view of the case in which the working parts operate, and 45 Fig. 4 is a detail of a certain lever having integral pins for rollers and serving as one of the electrical terminals of the device.

In said drawings, *a* indicates the case, which 50 consists of a single plate bent as shown in Fig. 3.

a' indicates the face-plate portion, which is 55 of a width equal to that of the parting-strip of the window-frame in which the device is secured, as indicated in Fig. 1, the ends of 60 said face-plate being perforated and forming ears *a'' a''* to lie on the outer face of said parting-strip. At the sides of said face-plate are extensions *a''' a'''*, which are bent at 65 right angles to said face-plate, so as to form 70 side plates, between which a wooden or non- 75 conducting block *b* is fastened. At one end 80 of each of said side-plate extensions the same

are again bent, as shown at *a'''' a''''*, to form 85 end plates of the case, side openings *c c* being formed between the ends of said side- 90 plate extensions and said end plates, through 95 which certain rollers *f* project to engage the window-sashes on opposite sides of the part- 100 ing-strips.

Between the extensions *a''' a'''* on the rear 105 side of the face-plate *a'* a pivotal pin *d* is secured or arranged, and on said pin is ful- 110 crumed a lever *e*, which lies diagonally be- 115 tween said side extensions, so that the roll- 120 ers *f*, carried by integral pins *f'*, cast upon 125 said lever near the opposite ends thereof, will 130 lie in said openings *c c* and project laterally 135 beyond the case, so that when the window- 140 sash is raised the same will engage one of 145 said rollers and press the same back, turning 150 the lever on its pivot or fulcrum, as will be 155 understood. The rollers are held in their 160 projecting positions (indicated in Fig. 1) by 165 a spring *g*, coiled upon the pin *d*, and bear- 170 ing at one end on the lever and at the other 175 on the case *a*. The spring may be disposed 180 in any other suitable manner to maintain the 185 normal projecting positions. The block *b* is 190 fastened between the side extensions *a'''* at 195 the rear of the said lever by screws *h*, and on 200 the same is arranged a contact-spring *i*, which 205 is fastened to said block by screws *j j*, said 210 contact or terminal spring being angularly 215 bent to extend over the end of the block to a 220 position to engage one end of the lever and 225 form scraping electrical contact therewith 230 when said lever is pressed to its abnormal po- 235 sition within the case. One of the screws 240 that hold the contact-spring in position and 245 one of the screws that hold the block in the 250 case serve as binding-screws for the conduct- 255 ing-wires.

In operating the circuit-changer when the 260 same is arranged in connection with a win- 265 dows and suitable electrical conducting-wires, 270 a battery, and alarm devices, and the said 275 changer is in its normal position, when either 280 of the window-sashes is moved it engages 285 one of the rollers, so that the same is pressed 290 back with its lever, and the latter engages 295 and scrapes the end contact-spring. The ter- 300 minals being thus brought into connection 305 the alarm mechanisms are operated in any 310 usual manner.

The device may be employed with either an open or closed circuit without material change in construction.

The opening *c* between the block *b* and face-plate *a'* is of a width equal or approximating the combined thickness of the lever *e* and roller, and inasmuch as the roller does not lie entirely out of the opening it is held on its pivot *f'* without riveting.

Having thus described the invention, what I claim as new is—

1. The improved burglar alarm circuit changer for windows, in which is combined, with a case having a face plate and side extensions arranged at opposite sides of said face plate at right angles thereto and having a pin, *d*, between said extensions, a contact lever, *e*, arranged on said pin and at its opposite ends having pins *f'*, carrying rollers, *f*, *f*, which normally project, through openings, *c*, *c*, beyond said side extensions, and a block, *b*, of insulation also arranged between said side extensions and holding said lever in place and the said rollers *f*, on the said

pins *f'*, of the lever, said block carrying a spring contact piece, substantially as set forth.

2. The improved burglar alarm circuit changer for windows, in which is combined with a case having a face plate and a pin *d*, at the back thereof, a lever arranged on said pin and projecting laterally at its opposite ends beyond the opposite edges of said face plate and at said opposite ends carrying rollers, a block of insulation back of said lever, and holding the same in place and a contact spring fastened to said block and extending into the path of the said lever, the latter scraping the edge of said spring longitudinally when forced to its abnormal position, substantially as set forth.

In testimony that I claim the foregoing I have hereunto set my hand this 11th day of October, 1894.

A. ALEXANDER VANDERPOOL.
